MEANS FOR CONDENSING AND REFINING
EXHAUST GASES

Hans Lundquist, Chicago, Ill., assignor of one-half to Frederick L. Maytag, Newton, Iowa

Application January 10, 1934, Serial No. 706,013

3 Claims. (Cl. 123—119)

The present invention relates to exhaust condensers and more particularly to a novel means for condensing, collecting and refining the usable portions or content of the exhaust gas for re-use in the combustion engine.

5 Among the objects of the present invention is to provide a novel means for condensing the hot or raw exhaust gases and treating and collecting the liquefiable and combustible content for re-use.

10 Another object of the present invention is the provision of a novel attachment adapted to be inserted in the exhaust line for condensing and collecting the unused combustible portions of the raw exhaust gas.

15 A further object of the invention is in the novel means for condensing the hot or raw exhaust gas by a cooling fluid. In the present embodiment, this cooling fluid is caused to circulate through the condenser by means of a radiator, and whereby the liquefiable content of the exhaust gas passing therethrough is condensed and collected.

20 A still further object of the present invention is in the provision of a novel system and means for condensing, collecting, filtering and purifying the combustible content or portions of the raw exhaust gas, and returning the separated portions to the fuel system for re-use.

25 Yet another object and distinct advantage of the invention is in the increased efficiency of operation of the automobile. The invention is constructed and arranged so as not to obstruct the normal flow of exhaust from the engine.

30 A further object of the present invention is in the provision of a compact and self-contained condenser and filter built and installed as a unit and which requires but a very limited space for installation.

35 Further objects are to provide a construction of maximum simplicity, efficiency, economy and ease of assembly, and such further objects, advantages and capabilities as will later more fully appear, and are inherently possessed thereby.

40 The invention further resides in the combination, construction and arrangements of parts illustrated in the accompanying drawings, and while there is shown therein a preferred embodiment, it is to be understood that the same is susceptible of modification and change and comprehends other details and constructions, without departing from the spirit of the invention.

45 In the drawings:

Fig. 1 is a diagrammatic view of an automobile equipped with the present invention.

Fig. 2 is a view in horizontal cross section through the condenser.

Fig. 3 is a view in vertical cross section through the condenser and receptacle for collecting the condensate.

Fig. 4 is a view in vertical cross section of the condenser taken in a plane represented by the line 4—4 of Fig. 3.

Fig. 5 is a view in horizontal cross section taken in a plane represented by the line 5—5 of Fig. 3.

Fig. 6 is a view in vertical cross section through an alternate construction.

Fig. 7, 8, and 9 are views in vertical cross section taken in planes represented by the lines 7—7, 8—8 and 9—9 respectively, of Fig. 6.

Referring more particularly to the disclosure in Figs. 1 to 5 inclusive, the novel device 1 is mounted in the exhaust line 2 leading from the internal combustion engine 3 of an automobile 4. The device is provided with a casing or housing 5 having its one end 6 made removable for permitting access to the interior. This end or closure 6 is normally held in place by suitable securing means such as bolts or the like 7 and is formed with an extension 8 forming a bearing for an end 9 of the exhaust pipe 2. The opposite end 10 is also provided with an extension 11 forming a bearing for the end 12 of the exhaust pipe.

Within the casing or housing 5 is positioned a radiator 13 forming a condenser for condensing the liquefiable portions or content of the exhaust gases. This radiator is provided with imperforate end plates 14 and 15, each having an edge seating against a shoulder 16 and 17, respectively, the opposite edges being spaced from the side walls of the casing to allow the passage of the exhaust gas.

The radiator is located and positioned in spaced relation within the casing by means of pins or projections 18 at one end on the end plate 15 and adapted to seat in openings in bosses 19 formed or provided on the interior of the end or closure 6. The opposite end plate 14 is provided with a pair of spaced bushings 20, each provided with an enlargement forming a spacer 21. Within the upper bushing is a conduit 22 forming an outlet for a cooling fluid, while in the lower bushing is a conduit 23 forming an inlet for the cooling fluid. A lock nut 24 on the threaded portions of each bushing 20 retains the radiator or condenser in proper position.

The exhaust gas in passing into and through the condenser follows the path of the arrows as shown in Fig. 2, entering at one side of the radiator and passing crosswise therethrough or transverse to the axis of the casing 5. The cooling fluid entering through the pipe or conduit 23 which is connected to the lower end or base of the ordinary radiator 25 passes into the lower pan 26 of the radiator 13, then passes upwardly through the core of the radiator to the upper pan 27 thereof from where the fluid passes through the conduit 22 and into the water jacket of the engine.

The condensate passes downwardly through the radiator and collects on the bottom 28 of the casing 5. This bottom slopes inwardly as shown in Figs. 3 and 4 whereby the condensate will collect and flow towards the center drain and through an outlet tube 29 into a receptacle 30. This receptacle is threaded onto a depending threaded part 31 on the base or bottom 28 of the casing. The part 31 is provided with spaced lugs or projections 32 which seat and retain a filter pad 33 on an annular shoulder 34 formed on the inner wall of the receptacle 30.

In order for the separated and collected fluid or liquid 35 to again pass into the fuel supply line of the engine, this fluid must pass through the filter 33 and thence through an outlet 36 to a conduit 37 which is connected to the vacuum tank 38 or other fuel supply means for transmitting the combustible fluid to the carburetor 39.

In Figs. 6 to 9 inclusive is disclosed an alternate embodiment of the invention in which the one end of the exhaust pipe 2 is connected to a casing or housing 40. This casing is provided with opposite end walls 41 and 42 which may be removable. The end wall 41 is provided with a reduced part or inlet 43 forming a bearing for one end of the exhaust pipe, while the end wall 42 is provided with a reduced part 44 forming a bearing for the other end of the exhaust pipe.

Mounted on the end wall 41 is a member 45 provided with a deflector or baffle 46 and peripheral openings 47 for the entrance of the exhaust into the interior of the casing 40, the baffle preventing the exhaust from passing directly through the casing but deflecting it so that this gas must pass in a tortuous path. Within the casing is suitably positioned a condenser 48 in the form of a radiator having tubes 49 for the passage of the gas and about which tubes is circulated a cooling fluid. This cooling fluid enters at the inlet 50 and passes out through the outlet 51 and may be connected in the circuit of the usual cooling radiator of the engine.

The gas escaping from the condenser will strike against the staggered deflectors or baffles 52 and 53 which are suitably mounted on the end wall 42 of the casing and maintained in their adjusted position by means of rods or spacers 54, 55, and 56. By causing the gas to strike against these deflectors or baffles 52 and 53, it is prevented from carrying any condensate suspended therein into the outlet 44 but such condensate will collect on these deflectors and drop into the tapered sump 57 along with the condensate which collects in the tubes 49 and drains therefrom.

As in the embodiment disclosed in Figs. 1 to 5 inclusive, the collected condensate flows through the pipe or outlet 29 into the receptacle 30 and before passing to the vacuum tank or fuel supply system, must pass through the filter 33 so as to remove any solid particles or foreign matter. The collected particles or foreign matter may be re-

moved through the removable cap 58. By removing the receptacle 30, the filter may be cleaned or replaced.

From the above description and the disclosure in the drawings, it will be readily apparent that the invention will provide a great saving in fuel and greatly increase the efficiency of the engine. The device may be readily installed, is compact and self-enclosed and is so constructed, arranged and proportioned as to permit a proper discharge of the exhaust gas without building up a back pressure on the engine.

Having thus disclosed the invention, I claim:

1. A device for condensing and separating the liquefiable and combustible content of the exhaust gases discharged from an internal combustion engine, comprising in combination, a casing, a condensing element in said casing having a water receiving side and an exhaust gas receiving side, portions of said condensing element being spaced from the interior of said casing to form water inlet and outlet spaces, a pipe connection to said water inlet space from the water cooling system of the internal combustion engine, a pipe connection from said water outlet space back to said water cooling system, a connecting conduit from the exhaust pipe of said engine to the exhaust gas receiving side of said condensing element, a receptacle for collecting the condensate from said condensing element, means for conducting said collected condensate back to the intake of the engine for reuse therein, and means for conducting the uncondensed exhaust gases from said condensing element to the outside atmosphere, whereby the water from the cooling system of the engine will be used for condensing a portion of the exhaust gases, and only the condensate will be returned therefrom to the engine for reuse therein.

2. A device for condensing and separating the liquefiable and combustible content of the exhaust gases discharged from an internal combustion engine, comprising in combination, a casing, a condensing element in said casing having a water receiving side and an exhaust gas receiving side, portions of said condensing element being spaced from the interior of said casing to form water inlet and outlet spaces, a pipe connection to said water inlet space from the water cooling system of the internal combustion engine, a pipe connection from said water outlet space back to said water cooling system, a connecting conduit from the exhaust pipe of said engine to the exhaust gas receiving side of said condensing element, a receptacle for collecting the condensate from said condensing element, means for conducting said collected condensate back to the intake of the engine for reuse therein, and means for conducting the uncondensed exhaust gases from said condensing element to the outside atmosphere, whereby the water from the cooling system of the engine will be used for condensing a portion of the exhaust gases, and only the condensate will be returned therefrom to the engine for reuse therein; and filtering means through which the condensate passes after leaving the condensing element to purify the same before entering the engine for reuse therein.

3. A device for condensing and separating the liquefiable and combustible content of the exhaust gases discharged from an internal combustion engine, comprising in combination, a casing arranged to be installed in the exhaust line, a heat exchange device in said casing

constructed and arranged that the hot exhaust gases will pass into said heat exchange device on one side and water from the cooling system on the other side, a connection from the inlet portion of the water side of said heat exchange device to the cooling system radiator of the engine, a return connection from the outlet portion of said water side back to the cooling system of the engine, a connection from the exhaust pipe of the engine to the exhaust gas side of said heat exchange device for the introduction of exhaust gases from the engine into said exhaust gas side, an outlet connection from the exhaust gas side of

said heat exchange device to the atmosphere for discharge to the atmosphere of the uncondensed portion of the exhaust gases, whereby the liquefiable and combustible content of the exhaust gases will be condensed in said heat exchange device by the water from the cooling system of the engine, means for conducting the condensate back to the intake of the engine for reuse in said engine, and filtering means between said heat exchange device and said engine for filtering said condensate before it is introduced into the engine.

HANS LUNDQUIST.
